UNITED STATES PATENT OFFICE

2,199,047

PNEUMATIC CUSHION

Norman Fisher, Eagle Grove, Iowa

Application February 24, 1939, Serial No. 258,337

4 Claims. (Cl. 155—179)

This invention relates to pneumatic cushions for seats such as employed on farming implements for the purpose of absorbing shocks and jars as well as providing a comfortable rest and may be employed in boats and if need should occur may be utilized as a life preserver. The primary object of this invention is the provision of a device of the above stated character which may be readily adjusted to fit seats of different sizes and shapes and may have its cushioning qualities increased and decreased by increasing and decreasing the air pressure in the inflatable tubes thereof and may be readily changed from one seat to another.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a top plan view illustrating a cushion constructed in accordance with my invention.

Figure 2 is a sectional view taken on the line 2—2 of Figure 1.

Figure 3 is an elevational view illustrating the front edge of the cushion.

Figure 4 is an elevational view illustrating the rear edge of the cushion.

Figure 5 is a plan view illustrating the inflatable tubes.

Referring in detail to the drawing, the cushion is indicated in entirety by the character 5 and consists of an outer covering 6 constructed of any material suitable for the purpose capable of withstanding severe wear and strain. Arranged in the covering 6 are inflatable pneumatic tubes 7 and 8. The inner tube 7 is arcuately curved or substantially U-shaped having the inflating valve 9 located intermediate its ends. The inflatable tube 8 is of a shape arranged to fit within the tube 7 and includes portions 10 and 11 joined by a portion 12. The portions 10 and 11 have arcuately curved edges to conform to the contour of the inflatable tube 7 and is also provided with straight parallel edges 13 and a straight edge 14 which is in a plane with the ends 15 of the inflatable tube 7. The straight edge 14 has an inflating valve 16 connected thereto positioning the inflating valve 16 directly opposite the inflating valve 9.

The inflatable tubes 7 and 8 are arranged in the outer covering and the latter has its opposite walls stitched or otherwise secured together,

as at 17, to separate the tubes 7 and 8 from each other and the portions 10 and 11 of the tube 8 from each other.

The tube 7 being of the shape shown in Figure 5 will readily conform to the contour of the upturned walls of a farm implement seat while the tube 8 rests flatly on the seat portion of the seat and by varying the amount of air pressure in the different tubes the cushion will readily conform to the seat of the farm implement and also by varying the air pressure the cushioning qualities of the cushion may be varied.

The covering 6 is provided with slots 18 in opposite walls thereof to permit the tubes 7 and 8 to be inserted in the proper compartments of the covering which are formed by the stitching of opposite walls of the covering together, as shown at 17. The slots 18 permit the inflating valves to extend outwardly of the covering and the latter along the slots 18 are provided with eyelets 19 through which lacings 20 may be passed for closing the slots of the covering about the inflating valves.

Attaching straps 21 are secured to the covering, one of which is equipped with a buckle 22 to engage with eyelets 23 provided in the other strap whereby the cushion may be readily strapped onto a seat of a farming implement or similar device. Any number of straps and buckles may be provided on the device to suit the different kinds of seats on which the device may be adapted.

It is preferable that the inner curved edge of the inflating tube 7 taper to a knife edge while the outer edge is rounded in cross section to permit the tube 7 to more readily conform to the upstanding walls of a farm implement seat.

It is believed that the foregoing description, when taken in connection with the drawing will fully set forth the construction and advantages of this invention to those skilled in the art to which such device relates, so that further detailed description will not be required.

What I claim is:

1. A pneumatic cushion comprising inner and outer interfitting inflatable tubes one being of substantially U shape and the other being shaped to fit within the former, a covering for said tubes, said covering having opposite walls thereof stitched together between the tubes to separate the tubes from each other.

2. A pneumatic cushion comprising inner and outer interfitting inflatable tubes one being of substantially U shape and the other being shaped to fit within the former, a covering for said tubes,

- said covering having opposite walls thereof stitched together between the tubes to separate the tubes from each other, oppositely arranged inflating valves on said tubes, said covering having slits to permit the inflating valves to extend outwardly thereof, and lacings securing the slits of the cover together about the inflating valves.
3. A pneumatic cushion comprising inner and outer interfitting inflatable tubes one being of substantially U shape and the other being shaped to fit within the former, a covering for said tubes, said covering having opposite walls thereof stitched together between the tubes to separate the tubes from each other, oppositely arranged inflating valves on said tubes, said covering having slits to permit the inflating valves to extend

outwardly thereof, lacings securing the slits of the covering together about the inflating valves, and attaching straps including fastening means for attachment to a seat.

4. A pneumatic cushion comprising a substantially U shaped inflatable tube, a second tube fitting within the substantially U shaped inflatable tube and including separable portions and a connecting portion between the separable portions, inflating valves for said tubes, and a covering encasing said tubes and having opposite walls thereof stitched together by the stitching passing between the tubes and the separable portion of the second-named tube.

NORMAN FISHER.
